UNITED STATES PATENT OFFICE.

JAMES ADAMS, OF GLASGOW, GREAT BRITAIN.

GAS-STOVE.

SPECIFICATION forming part of Letters Patent No. 233,389, dated October 19, 1880.

Application filed December 5, 1879. Patented in England March 19, 1879.

To all whom it may concern:

Be it known that I, JAMES ADAMS, of Glasgow, county of Lanark, in the Kingdom of Great Britain and Ireland, have invented new and useful Improvements in Gas-Stoves, of which the following is a specification.

This stove is specifically designed for heating apartments, but the burner thereof is adapted to either cooking or heating stoves of various kinds. The burner is made of a number of perforated tubes of fire-clay or other refractory material supported upon a perforated plate. The gas passes to the burner-tubes through short metal tubes connected with a gas-supply box, and there is a space between the burner-tube and the gas-tube to allow air to be drawn into the burner-tube and mix with the gas. The amount of air drawn in is regulated by a ring-slide upon the case that surrounds the burner, there being openings in the case that are closed more or less by the position of said ring-slide.

The products of combustion from the burner pass upward through a flue divided by horizontal plates into several chambers, and there are openings in these plates so arranged that the products of combustion are caused to travel in a circuitous or zigzag path through the flue, and are detained therein, so as to give off all their available heat to the casings that form the walls of said flue, and thus heat the air that ascends in flues adjacent to this zigzag flue.

The air that is drawn into the stove to be heated passes in near the top of the stove, so as to avoid making drafts near the floor, and the heated air, before leaving the stove and entering the apartment, passes over water in a trough surrounding the upper part of the stove, to promote evaporation and restore to the heated air the humidity lost by passing through the stove.

In the drawings, Figure 1 is a vertical section of the heating-stove, and Fig. 2 is a partial horizontal section of the same at the line 1 1. Fig. 3 is a vertical section, and Fig. 4 is a horizontal section, one half being at the line 3 3 and the other half at the line 4 4. It shows a cooking-stove fitted with my improved burner. The other figures are separately referred to.

The base of the stove is made as a box or

chamber, D, supported upon feet f, and into this chamber D the cold air is drawn through the vertical pipe G, the upper open end of which is near the middle part of the stove, so as to prevent drafts near the floor.

Beneath the chamber D there is a shallow box, A, into which the gas passes by the pipe g, and the amount thereof is regulated by the cock g'. The top plate of this box receives short metal tubes a, and immediately over these gas-tubes are placed the burner-tubes b, which are supported in sockets upon the plate b', that is perforated around each burner-tube, to admit air to supply the jets of gas that burn outside the tube b.

There are annular openings between each gas-tube a and its burner-tube b, to admit air within the burner-tube to commingle with the gas, and there is a plate, a³, below the burner-tubes, through which plate the gas-tubes a pass, and the opening through which the tubes pass should be of a size to allow sufficient air to pass to the burner-tubes.

The burner-tubes b are within the casing D', that shields the burner from lateral currents of air, and in this casing there are openings at a⁴, that may be opened or closed more or less by the ring-slide D⁵ to regulate the amount of air to the burner. This slide may be operated by a rod extending from the slide to the outside casing of the chamber D, or there may be a door at k, Fig. 2, to give access to this ring-slide or for lighting the burner. This door may have openings covered by mica or similar material, so that the light of the burner may be seen, and thus give a cheerful appearance to the stove. To provide for this there is an opening at that side of the casing D', and partitions k² extend from the sides of this opening to the casing of the chamber D, so that the air in said chamber cannot pass through the opening in the casing D' to the burner.

The mixture of gas and air burns at the exterior of the tubes b, and by the construction of burner aforesaid the flame can be of greater or less intensity without danger of smoking.

The gas-supply box A being located near the burner-tubes, the gas in said box becomes heated, as does also the air in the chamber above such box; hence the air and gas more

thoroughly commingle in the burner-tubes and a more perfect combustion is obtained.

Instead of the burner-tubes being cylindrical, they may be hexagonal, as in Fig. 7; or, in 5 place of several burner-tubes, the double cylinder (shown in Fig. 8 by plan and section) may be employed.

The body portion of the stove is composed of two casings or cylinders, D² D³, of sheet 10 metal, supported by the plate k' of the air-chamber D, and the space between the two cylinders becomes a flue, d⁴, for the passage of the air that is to be heated, the top plate, k', being provided with one or more openings 15 to allow the air to pass into the said flue d⁴.

Inside the cylinders D² D³, Figs. 1 and 2, there is a smaller cylinder or casing, H, suspended from the ring D⁶, and this cylinder is open at the top and has a closed bottom, B⁷, 20 and said bottom is immediately over the burner, but at the proper distance therefrom, so that the products of combustion can freely pass to the flue C between the casings H and D³.

There is a tube, H', within H, suspended 25 from the top E' of the stove, and this tube is open at both ends, and there is a space, h, between H' and H for the air that is drawn down the tube H' to ascend and be warmed by the heated products of combustion that pass up 30 the flue C. The flue C is divided into several chambers by means of the horizontal plates C', and these plates have openings arranged alternately on opposite sides, as shown in Fig. 1, so that the products of combustion are detained in this flue and obliged to travel in a spiral or zigzag path before escaping by the 35 pipe J to the chimney. By this construction of flue the casings D² and H become highly heated, and the air that ascends in the flues 40 d⁴ and h becomes highly heated by contact with the casings D³ and H of the flue C.

Air-tubes may pass through the flue C, as shown by dotted lines at F, Figs. 1 and 2, the air entering such tubes from the chamber D.

45 The heated air from the flues d⁴ and h, before escaping into the room through the open-work of the top E, passes over water contained in an annular trough, E², that surrounds the upper part of the cylinder D², so as to promote 50 evaporation of the water and return to the heated air the moisture lost in passing through the stove.

To prevent the bottom B⁷ of the cylinder H being injured by the flame of the burner, it 55 may be made of fire-clay or similar material; or the burner may be surrounded by the perforated fire-clay dome B⁹, Fig. 5, to protect said cylinder H, and also the metal contiguous to the burner, from injury by the flame.

60 The burner before described is adapted to cooking and other forms of stoves.

Referring to Figs. 3 and 4, a cooking-stove is shown made of the casings C⁹ and C¹⁰, supported upon the air-chamber D, to which latter air is admitted by the pipe G. 65

The plate C¹² forms the top of the main oven C⁸, and above this there are ovens or chambers C².

My improved burner is placed at the upper part of the stove for heating the chambers C² 70 at the sides of such burner, and a burner is placed at the lower part of the stove for heating the oven C⁸. The heat from the lower burner and from this oven passes through the chambers C² before escaping by the pipe J to 75 the chimney.

The construction of this cooking-stove is not claimed herein, and Figs. 3 and 4 are introduced for the purpose of showing how the burner may be used in cooking as well as in 80 heating stoves.

I claim as my invention—

1. The combination, in a burner for a gas-stove, of the perforated tubes b, gas-tubes a, perforated plates b' and a³, jacket or casing D', 85 and slide D⁵, substantially as and for the purposes specified.

2. In combination with a burner consisting of the tubes b and a, plates b' and a³, casing D', and slide D⁵, the gas-supply box A beneath 90 and adjacent to the burner, substantially as and for the purposes specified.

3. In a gas-stove for heating, a central tube, H', and cylinder H, in combination with the cylinder D³ and intervening flue C, surrounding the flue h, and a burner for heating the flue C, substantially as and for the purposes 95 specified.

4. In a gas-stove for heating, the casings D² D³, cylinder H, and tube H', arranged as 100 specified, to form the flues d⁴, e, h, and h', in combination with a burner for heating the stove, substantially as specified.

5. In a gas-stove for heating, the burner enclosed by a casing, D', in the air-chamber D, 105 in combination with the pipe G and flues d and C, substantially as and for the purposes specified.

6. In a gas-stove for heating, the casings D² and D³, cylinder H, and tube H', arranged 110 as specified, in combination with the trough E² and top plate, E', substantially as and for the purposes set forth.

7. The combination, in a burner for a gas-stove, of the perforated tubes b, gas-tubes a, 115 perforated plates b' and a³, and jacket or casing D', substantially as and for the purposes set forth.

JAMES ADAMS.
